UNITED STATES PATENT OFFICE.

EDWIN H. BRODEN, OF SWISSVALE, JOHN A. FEIERABEND, OF WILKINSBURG, AND HARVEY B. TROTT, OF MCKEESPORT, PENNSYLVANIA.

BUNDLING MACHINE.

Application filed May 13, 1927. Serial No. 191,070.

This invention relates to machines for tying annular bundles of wire, and has for its object the provision of such a machine which will be automatic in operation after it is once set in motion and until a plurality of ties are made on a bundle of wire.

Another object is to provide a machine of this class which is adapted to tie bundles of wire of various diameters.

10 A further object is to provide a machine having the general combination, design, and construction of parts hereinafter described and illustrated in the accompanying drawings.

15 In the drawings—

Figure 1 is a plan view of the machine as a whole.

Figure 2 is an enlarged partial longitudinal vertical section through the machine.

20 Figure 3 is a similar view through the remainder of the machine.

Figure 4 is a transverse sectional view on the line IV—IV of Figure 1.

Figure 5 is a transverse sectional view on the line V—V of Figure 1.

Figure 6 is a partial longitudinal section on the line VI—VI of Figure 1.

Figure 7 is a sectional view taken on the line VII—VII of Figure 6.

30 Figure 8 is an end view of the machine with the cover plate removed, showing the drive gearing.

Figure 9 is a sectional view taken on the line IX—IX of Figure 8.

35 Figure 10 is a sectional view taken on the line X—X of Figure 8.

Referring more particularly to the drawings, the numeral 2 designates the frame or base of the machine as a whole, which is in the form of a heavy casting, adapted to be bolted or otherwise secured to a suitable foundation (not shown).

40 A pair of carriage members 3 and 4 are slidably mounted in spaced relation on the frame 2 and adapted to be moved toward or away from each other by threaded adjusting rods 5 and 6, respectively, journaled in fixed

50 engagement with the respective carriages 3 and 4 and are provided with hand wheels 9

55 A pair of material supporting rollers 10 are journaled on shafts 11, one of which extends transversely of each of the carriages 3 and 4 and is journaled in bearings 12 on such carriages.

60 The rollers 10 are adapted to be rotated by the shafts 11 through a clutch connection composed of a spring pressed pawl or dog 11^a carried in an arm 11^b keyed on the shaft 11 and adapted to engage the ratchet teeth 10^a formed in the rollers 10. This clutch 65 connection permits free rotation of the rollers 10 in one direction when positioning the bundles of wire thereon.

65 Each of the carriages 3 and 4 is provided with a bearing arm 13 which projects toward the rear of the machine and terminates in a bearing 14. A bevel gear 15 is journaled in each of the bearings 14 and each of said gears is provided with a squared opening to

70 slidably receive a squared portion 16 of a drive shaft 17. A bevel gear 18 is secured on the rear end of each of the shafts 11 and meshed with the respective gears 15 so that when the shaft 17 is rotated the shafts 11 and rollers 10 will be rotated to advance 75 the material to be tied.

75 A sprocket 20 is mounted on the shaft 17 adjacent its one end and is connected to a sprocket 21 on a drive shaft 22 by a chain 23. The shaft 22 is journaled in bearings 24 and 25 and has one end projecting through the end of the frame 2 and provided with a drive gear 26.

80 A segmental ring gear 27 is mounted in a vertically disposed guide casing 28 on the frame 2 between the material supporting rollers 10, which casing has its upper portion cut away a distance equal to the space between the ends of the segmental ring gear 27. The opening in the gear ring 27 is 85 adapted to be aligned with the opening in the casing 28 to form an open throat through which the annular bundles of wire or other material being tied or wrapped is adapted to project when supported on the rollers 10.

90 The casing 28 is extended toward the front and rear sides of the machine to form drive gear housings 28^a and 28^b, respectively, to the frame 2. The housings 28^a and 28^b are journaled in bearings 31 and 32 on the

95 drive shaft 22 and are provided with a gear 29 meshed with the ring gear 27. The gear 29 is housed in the housing 28^a. The gear 29 is keyed on one end of a drive shaft 30 100 journaled in bearings 31 and 32 on the

frame 2, and a gear 33 is keyed to the opposite end of said shaft.

A gear 34 is also meshed with the ring gear 27 and is housed in the housing 28.

5 The gear 34 is keyed on one end of a drive shaft 35 journaled in bearings 36 and 37 on the frame 2, and a gear 38 is keyed to the opposite end of the said shaft.

The gears 33 and 38 are meshed with a 10 single idler gear 39 journaled on a stub shaft 40 secured in the frame 2. A pinion 41 is keyed to the end of a drive shaft 42 and meshed with the idler gear 39. The shaft 42 extends from end to end of the machine and 15 has a drive pinion 43 keyed to the end opposite from the pinion 41.

The gears 29 and 34 engage the ring gear 27 at points a greater distance apart than the length of opening in the ring gear so 20 that one of said gears will always be in driving engagement with the ring gear segment.

A spool support 44 is secured to the ring gear 27 and is provided with a spindle 45 25 on which is mounted a spool of tying wire 46 for wrapping and tying the bundles of wire. A wire guide 47 is also secured to the support 44.

In operation when the ring gear 27 is 30 rotated in the casing 28 the spool of tying wire 46 will be around the annulus of the annular bundle of wire, forming a plurality of wraps.

In order to secure or tie the wraps of 35 tying wire, a twisting mechanism is provided for twisting the several wraps of tying wire together. The twisting mechanism comprises a vertical spindle 48 mounted in a bearing 49 in the frame 2 and having a 40 disk 50 secured to its upper end. A twister post 51 having a base 52 is secured on and adapted to rotate with the disk 50. A tapered twisting finger 53 is secured to the post 51 and adapted to project outwardly 45 under the bundle of wire being tied, so as to lie between the bundle and the wraps of tying wire, that is, the tying wire is adapted to be wrapped around the bundle and finger 53.

50 The spindle 48 has a bevel gear 54 keyed to its lower end which gear is meshed with a bevel gear 55 on a shaft 56 which is journaled in bearings 57 on the frame 2 and projects through the end of the frame. A 55 drive pinion 58 is keyed to the end of the shaft 56, projecting through the end of the frame 2.

When the shaft 56 is rotated the gears 54 and 55 will be rotated so as to rotate 60 the spindle 48 and twisting finger 53, thus twisting the wraps of tying wire together. When the wraps of tying wires are twisted together by the finger 53 a tight loop is formed on the finger and in order to remove this loop as the rollers 10 are rotated 65

to advance the bundle of wire being tied, we provide a kicking or stripping mechanism to kick the loop free on the finger 53.

The kicking or stripping mechanism comprises a stripping frame 60 slidably mounted 70 on the finger 53 and having a pair of downwardly extending ears 61 which project downwardly on each side of the post 51. A leaf spring 62 is secured at one end to the post 51 and has its other end loosely engaging a transverse pin 63 extending between the ears 61, so as to normally hold the stripping frame 60 in retracted position.

A rock shaft 64 extends transversely of the frame 2 and is journaled in bearings 65. 80 An actuating arm 66 is keyed on the shaft 64 and is adapted to engage the ears 61 of the frame 60 when the shaft 64 is rocked and thus move the frame 60 forwardly along the finger 53 to kick or strip the loop of 85 tying wire loose on the finger.

The shaft 64 is adapted to be rocked by a lever 67 which is secured intermediate its ends on the shaft 64 and has a link 68 pivotally secured to one end and extending 90 downwardly through a guide 69 secured to the frame 2. The link 68 has a roller 70 thereon adapted to be engaged by a cam 71 secured to the drive shaft 22 so that said cam will lift the roller 70 and link 68 at 95 the start of the shaft 22, thereby operating the stripping frame at the start of the material supporting rollers 10.

The end of the lever 67 opposite that to which the link 68 is secured, has a plunger 72 pivotally secured thereto which is adapted to project downwardly through an opening in the frame 2 when the shaft 64 is rocked and to compress a coiled spring 73, which spring is adapted to return the shaft 105 64 and its accompanying mechanism to normal position after the high point of the cam 71 passes under roller 70.

In order to prevent the strand of wire leading from the spool 46 following the 110 bundle of wire being tied when the bundle is advanced, a combined wire guide and depressor arm 75 is provided which is pivotally supported intermediate its ends on a bracket 76 on the casing 28 and has one end 115 extending across the normal path of the strand of tying wire from the spool 46. The arm 75 has a wire guide slot or groove 77 through which the tying wire passes to the bundle to be tied. The opposite end of the arm 75 is pivotally connected to a plunger 78 which has a roller 79 journaled on a pin 80 secured in its lower end. The roller 79 is adapted to ride on a roller track 81 on the disk 50, which track has a raised point or cam 82 thereon adapted to force the roller 79 and plunger 78 upwardly at each revolution of the disk 50. The cam 82 is so positioned that it will raise the plunger 78 and thereby depress the arm 75 and the 130

strand of tie wire as the twisting finger 53 approaches such strand, thus moving the strand of the wire out of the path of the finger 53.

5 A spring operated return link 83 is pivotally connected to the pin 80 and extends downwardly through the frame 2 of the machine and carries a coil spring 84 which is compressed when the roller 79 is forced upwardly by the cam 82 and serves to return the parts to normal position as the cam 82 is moved from under the roller 79. The arm 75 is adapted to depress the strand of wire leading from the spool 46 into the path of the twisting finger 53 so that said strand will be twisted in the loop of tying wire.

The machine is adapted to receive its power from a single motor 85, mounted on a motor bracket 86 extending to the rear of the main frame 2. The motor shaft 87 is connected to a worm-shaft 88 by a flexible coupling 89. The shaft 88 is journaled in suitable bearings in a worm and worm-wheel casing 90 and carries a worm 91 which 25 is meshed with a worm-wheel 92 on a worm-wheel shaft 93 journaled in the casing 90. A main drive shaft 94 is journaled in bearings in the frame 2 and is adapted to be connected with the worm-wheel shaft 93 by 30 a clutch B, which is designed to hold in engagement for one revolution of the drive shaft only.

The clutch B comprises a clutch sleeve 95 secured or fixed on the worm-wheel shaft 93 and a second clutch sleeve 96 slidably mounted on the drive shaft 94 and adapted to mesh with and form a driving connection with the sleeve 95. The sleeve 96 is normally forced toward the sleeve 95 by a coil spring 97 and 40 is provided with a cam slot 98 in its periphery adapted to receive the free end of an actuating pin 99. When the pin 99 enters the slot 98 the walls of the slot will bear against the pin 99 as the sleeve 96 is rotated and retract the sleeve so that as the shaft 94 makes its complete revolution the sleeve 96 will be disengaged from the sleeve 95. The pin 99 is slidably mounted in a guide opening 100 in the frame 2 and has its lower 50 end pivotally connected to one end of a lever 101 on a rock shaft 102 journaled in bearings 103 on the frame 2. The shaft 102 has a second lever 104 secured thereto which is connected by a link 105 to a counter-weighted rocking operating lever 106 which 55 is provided with a foot-treadle 107. In operation the operator, by tramping on the treadle 107, will force the end of the lever 106 to which the link 105 is connected, downwardly and raise the counter-weighted end of the lever. This operation will rock the shaft 102 and withdraw the pin 99 from the groove or slot 98 so as to permit the 60 spring 97 to force the clutch sleeves into engagement. The movement of the sleeve 96

toward the sleeve 95 will move the slot 98 out of the path of the pin 99 so that the pin will engage and ride on the periphery of the sleeve 96 until the slot 98 again aligns with the pin when the pin will be forced 70 into the slot to withdraw the sleeve 96.

The main drive shaft 94 is provided with a mutilated or segmental gear 109 which is provided with a segment of teeth 110. A pinion stop guide ring 112 is mounted on 75 the gear 109 and is provided with a peripheral recess 113 in line with the segment of teeth 110.

A stub shaft 114 is secured in the end of the frame 2 and has a sleeve 115 journaled 80 thereon, which sleeve has a pinion 116 and gear 117 keyed thereon. The pinion 116 is adapted to be engaged by the segment of teeth 110 on the gear 109 and the gear 117 is meshed with the gear 26 on the shaft 22. 85

A second stub shaft 118 is secured in the end of the frame 2 and has a sleeve 119 journaled thereon, which sleeve has a pinion 120 and a gear 121 keyed thereon. The pinion 120 is adapted to be engaged by the segment 90 of teeth 110 on the gear 109 and the gear 117 is meshed with the pinion 58 on the twister drive shaft 56.

A third stub shaft 122 is secured in the end of the frame 2 and has a sleeve 123 journaled thereon, which sleeve has a pinion 124 and a gear 125 keyed thereon. The pinion 124 is adapted to be engaged by the segment of teeth 110 on the gear 109 and the gear 125 is meshed with an idler pinion 126 on a 100 stub shaft 127 secured in the end of the frame 2. The pinion 126 has an elongated neck 128 on which is keyed a gear 129 which is in mesh with the pinion 43 on the tie wire spool drive shaft 42. 105

The shafts 114, 118, and 122 are each spaced an equal distance from the center of the drive shaft 94 and from each other so that the segment of teeth 110 on the gear 109 will successively engage the pinions 124, 126 110 and 116 as the shaft 94 and gear 109 are rotated one complete revolution in a clockwise direction.

Each of the sleeves 115, 119, and 123 are 115 provided with a stop lug 130 adapted to have a sliding engagement with the periphery of the pinion stop ring 112 and thereby prevent rotation of the pinions until the recess 113 is moved into line with the lug, at which time the segment of teeth 110 of the gear 109 will engage the respective pinion and the recess 113 will supply the necessary clearance to permit the stop lugs 130 to rotate. As the segment of teeth 110 leave each of the respective pinions the lugs 130 will 120 again be engaged with the periphery of the ring 112 and lock the pinion against rotation. 125

In tying annular bundles of wire or the like by the use of the machine of this invention

tion, the bundle is placed on the supporting rollers 10, the tying wire is then drawn through the bundle and either secured to a stationary part of the machine or around the bundle. The operator will then tramp on the treadle 107 so as to withdraw the pin 99 and allow the clutch B to engage and start the machine. When the clutch engages, the segmental gear 109 will rotate 10 and the teeth 110 will first engage the pinion 124 and operate the train of gears 125, 126, 129 and 43 so as to rotate the shaft 42 and operate the gears 41, 39, 33, and 38. The gears 33 and 38 are keyed to the shafts 30 15 and 35, respectively, which also carry the operating gears 29 and 34 for the segmental gear ring 27 which carries the spool of tying wire. As the gears 29 and 34 are rotated they will rotate the gear ring 27 so as to 20 make two complete revolutions of the ring gear and consequently two complete wraps of tying wire around the annulus of the bundle of wire. It will also be noted that due to the position of the twisting finger 53, 25 the tying wire will also be wrapped under this finger so that when the wrapping is completed the finger 53 will be positioned between the wraps and the bundle in readiness to twist the wraps together. The gearing 30 is so arranged that the number of teeth in the drive gear segment 110 is sufficient to cause two complete revolutions of the ring gear 27.

After the gear 109 has moved past the pinion 124 it will next engage the pinion 120 and operate the gears 121 and pinion 58, so as to rotate the shaft 56 and gears 54 and 55, thus rotating the spindle 48 and disk 50 and the twisting finger 53. The gearing 40 120, 121, 58, 54, and 55 is so arranged that the teeth segment 110 of the gear 109 will be sufficient to operate such gears to cause two complete revolutions of the twisting finger 53. As the disk 50 is rotated the cam 45 82 will be moved under the roller 79, thus operating the guide and depresser arm 75 to move the strand of tying wire out of the path of the finger 53.

After the segment of teeth 110 of the 50 gear 109 has moved past the pinion 120 it will next engage the pinion 116 and operate the gears 117 and 26, so as to rotate the shaft 22. The shaft 22 will in turn drive the shaft 17 through the sprockets 20—21 and 55 chain 23, and the shaft 17 will in turn rotate the shafts 11, carrying the supporting rollers 10, through the bevel gears 15 and 18. The arrangement of gearing in this last named drive is such that the rollers 10 will 60 be rotated only sufficient to rotate the bundle of wire being tied a portion of a revolution so that a new point will be presented for tying.

The operation of the rollers 10 completes

one cycle of the operation of the machine 65 and the clutch sleeve or collar 96 will have revolved so that the pin 99 has again entered the slot or groove 98 and caused the sleeve 96 to be retracted to disengaged position and stopped the drive gear 109. 70

The operator will now be compelled to again tramp on the treadle 107 to start another cycle and complete another tie, and again advance the bundle of wire, the cycles being repeated until the desired number of 75 ties are made around the bundle.

While we have described and illustrated one specific embodiment of our invention it will be understood that we do not wish to be limited to the specific embodiment illustrated, since various modifications may be made without departing from the scope of our invention as defined in the appended claims. 80

We claim—

1. A machine for tying annular bundles of 85 wire comprising, a pair of bundle supporting rollers adapted to support the bundle of wire being tied, a spool supporting means adapted to revolve through and under said bundle of wire supported on said rollers, a 90 spool of tying wire on said spool supporting means, said tying wire being adapted to be wrapped around said bundle of wire when said spool supporting means is revolved, means for twisting said wraps of tying wire 95 together, means for revolving said supporting rollers to turn said bundle of wire after each twisting operation, and means for revolving said spool supporting means while 100 said supporting rollers and twisting means are stationary and inoperative.

2. A machine for tying annular bundles of 105 wire comprising, a pair of bundle supporting rollers adapted to support the bundle of wire being tied, a spool supporting means adapted to revolve through and under said bundle of wire supported on said rollers, a 110 spool of tying wire on said spool supporting means, said tying wire being adapted to be wrapped around said bundle of wire when said spool supporting means is revolved, means for twisting said wraps of tying wire 115 together, said means including a twisting finger adapted to be positioned between said bundle of wire and the wraps of tying wire, and power means for moving said finger through a circular path to twist said wraps of tying wire.

3. In a machine for tying annular bundles 120 of wire and having a pair of supporting rollers, and means for wrapping tying wire around the annulus of said bundles of wire supported on said rollers, a twisting mechanism adapted to twist the wraps of tying wire together, said mechanism comprising a spindle, a twister base on said spindle, a twister arm on said base, a twister finger 125 projecting outwardly from said arm and

- adapted to be engaged between the annulus of the bundle of wire and the wraps of tying wires, and means for rotating said spindle and twister parts.
4. In a machine for tying annular bundles of wire and having a pair of supporting rollers, and means for wrapping tying wire around the annulus of said bundles of wire supported on said rollers, a twisting mechanism adapted to twist the wraps of tying wire together, said mechanism comprising a spindle, a twister base on said spindle, a twister arm on said base, a tapered twister finger projecting outwardly from said arm and adapted to be engaged between the annulus of the bundle of wire and the wraps of tying wires, and means for rotating said spindle and twister parts.
5. In a machine for tying annular bundles of wire and having a pair of supporting rollers, and means for wrapping tying wire around the annulus of said bundles of wire supported on said rollers, a twisting mechanism adapted to twist the wraps of tying wire together, said mechanism comprising a spindle, a twister base on said spindle, a twister arm on said base, a tapered twister finger projecting outwardly from said arm and adapted to be engaged between the annulus of said bundle of wire and the wraps of tying wires, means for rotating said spindle and twister parts, and means for stripping the twisted tie wires from said twister finger.
6. A machine for tying annular bundles of wire comprising, a pair of bundle supporting rollers, a spool supporting means adapted to be revolved around the annulus of the bundle supported on said rollers, a spool of tying wire on said spool supporting means, the tying wire being adapted to be wrapped around the annulus of the bundle when said spool supporting means is revolved, means for twisting said wraps of tying wire together, a single driving motor, and means including a segmental drive gear adapted to be operated by said motor, and separate trains of gearing adapted to be operated in succession by said drive gear for driving said spool supporting means, said twisting means and said supporting rollers.
7. A machine for tying annular bundles of wire comprising, a pair of bundle supporting rollers, a spool supporting means adapted to be revolved around the annulus of the bundle supported on said rollers, a spool of tying wire on said spool supporting means, the tying wire being adapted to be wrapped around the annulus of the bundle when said spool supporting means is revolved, means for twisting said wraps of tying wire together, a single driving motor, and means including a segmental drive gear adapted to be operated by said motor and separate trains of gearing adapted to be op-
- erated in succession by said drive gear for driving said spool supporting means, said twisting means, and said supporting rollers, a spool of tying wire on said spool supporting means, and means for locking said separate trains of gearing against rotation when said drive gear is out of mesh therewith.
8. A machine for tying annular bundles of wire comprising, a pair of bundle supporting rollers, a spool supporting means adapted to be revolved around the annulus of the bundle supported on said rollers, a spool of tying wire on said spool supporting means, the tying wire being adapted to be wrapped around the annulus of the bundle when said spool supporting means is revolved, means for twisting said wraps of tying wire together, a single driving motor, means including a segmental drive gear adapted to be operated by said motor and separate trains of gearing adapted to be operated in succession by said drive gear for driving said spool supporting means, said twisting means, and said supporting rollers, and means including a stop ring carried by said drive gear and stop lugs rotatable with said trains of gearing and adapted to engage said stop ring when said drive gear is out of mesh with said trains of gearing for locking said separate trains of gearing against rotation.
9. A machine for tying annular bundles of wire comprising, a pair of bundle supporting rollers, a spool supporting means adapted to be revolved around the annulus of the bundle supported on said rollers, a spool of tying wire on said spool supporting means, the tying wire being adapted to be wrapped around the annulus of the bundle when said spool supporting means is revolved, means for twisting said wraps of tying wire together, a single driving motor, means including a segmental drive gear adapted to be operated by said motor and separate trains of gearing adapted to be operated in succession by said drive gear for driving said spool supporting means, said twisting means, and said supporting rollers, and a clutch for forming a driving connection between said segmental driving gear and said motor, means for controlling the operation of said clutch, said means being manually operated to permit engagement of said clutch and automatically operated to cause disengagement of said clutch after each revolution of said drive gear.
10. A machine for tying annular bundles of wire comprising, a main frame, a pair of carriages on said frame and adjustable toward or away from each other, a bundle supporting roller on each of said carriages adapted to support the bundle of wire being tied, a spool supporting means adapted to revolve through and under said bundle of wire supported on said rollers, a spool of tying wire on said spool supporting means,

said tying wire being adapted to be wrapped around said bundle of wire when said spool supporting means is revolved, means for twisting said wraps of tying wire together, 5 means for revolving said supporting rollers to turn said bundle of wire after each twisting operation, and means for revolving said spool supporting means while said support- ing rollers and twisting means are stationary and inoperative. 10 In witness whereof we have hereunto signed our names.

EDWIN H. BRODEN.
JOHN A. FEIERABEND.
